PRINTING TELEGRAPH APPARATUS

Raymond E. Zenner, Chicago, Ill., assignor to
Teletype Corporation, Chicago, Ill., a corpora-
tion of Delaware

Application November 25, 1938, Serial No. 242,408

20 Claims. (Cl. 178—4)

The present invention pertains to printing telegraph apparatus and more specifically to printing telegraph apparatus capable of tabular recording.

The invention has for its primary object the preparation of a control strip for controlling telegraphically the recordation of tabular matter efficiently and reliably.

Another object of the invention is to produce a signal control strip so perforated as to provide variable tabulation time intervals by inserting automatically in the control strip variable pluralities of tabulation-time code signals having non-spacing and non-printing attributes.

A feature of the invention resides in providing a keyboard perforator or keyboard transmitter, additional mechanism controlled by tabulator mechanism for automatically operating, for variable periods of time under the control of the tabulator mechanism, a function key lever provided with repeat mechanism, whereby the code signal controlled by said function key lever is repeated consecutively a number of times corresponding to the tabulation-time.

To achieve the above and other objects of the invention, a keyboard perforator and transmitter of the type disclosed in U. S. Patent No. 1,965,572 is modified for the production of perforated tape to be subsequently employed to control the transmission of message matter embodying tabulation operations.

In printing telegraph systems employing recording apparatus provided with tabulating mechanism, a variable interval of time is required to move the type carriage (or platen carriage, as the case may be) from one tabular position to another. This interval will be termed therein as "tabulating time." In the manual operation of key controlled recording apparatus cognizance is taken of tabulating time by the operator, who, during such time, refrains from operation of the keyboard. However, in automatic operation of such recording apparatus under remote control of tape transmitters wherein the apparatus is unattended for extended periods of time, it is desirable to simulate manual control during tabulation so as to maintain a tabulating condition automatically during the time that the carriage is in motion while tabulating, thus attaining proper tabular operation of the recording apparatus.

The present invention provides for the operative association of a keyboard perforator transmitter with a receiving printer, whereby the receiving printer may be made to respond to the

operation of the keyboard transmitter simultaneously with the perforation of a tape. Such an arrangement produces a printed copy or home record corresponding to the perforations in the tape, and allows the operator to determine easily and quickly by merely reading the printed message whether the perforated message is the message desired to be transmitted.

Specifically, when a perforated record is made involving tabulated portions, it is expedient to compensate for the tabulation time required at the recorder, either by suspending transmission during tabulation, as disclosed in U. S. Patents 2,104,071 and 2,104,110, or by employing the arrangement or method of the present invention, which continues transmission but suspends printing. In the type of tabulating recorder disclosed in U. S. Patents 2,104,071 and 2,104,110, a tabulator bar extends across the front of the machine, is carried by brackets mounted in the typing unit, and is capable of swinging toward and away from the type carriage. The tabulator bar carries a number of adjustable stop members which determine the distances through which the type carriage is automatically propelled, each of which distances is equivalent to a plurality of character spaces, following the reception of a tabulator code signal combination.

According to the method embraced by this invention, the tabulator key of the keyboard is operated to set the keyboard permutation elements for a tabulation initiation code signals, the home recorder responds to code signal impulses generated by the transmitter and effects the function of initiating the tabulating operation, causing the operation of the tabulating bar to close a contact in the circuit of a solenoid positioned above a function key lever; for example, the "Figures" key lever. This solenoid thus becomes energized and, through a repeat mechanism, initiates continuous and repeated operation of the transmitter. This setting of the keyboard permutation mechanism by the solenoid sets the transmitting elements for a tabulating time continuation code signal which has the function of consuming line time during the tabulation period. As the carriage moves during the tabulating time or period at the home recorder, the transmitter transmits repeatedly, and the tape perforator perforates repeatedly, the code signal for tabulating time continuation. This tabulating time continuation code signal preferably is selected so as to be ineffective upon any printing member, although this feature is not fundamental to the invention, since

were the hyphen type or period type or underscore type responsive to the signal, the result would be a line of printed characters of the nature selected, thus leading the eye of the reader from one tabulation column along a line of legibility to the next tabulation column, which effects may be desirable, particularly in case of tabulation columns widely separated upon a page. The continuation code signal also is desirably non-spacing in the sense that if such a signal were received by a receiving tabulating printer after the carriage has stopped in response to tabulation control, it is desirable that response to the continuation code signal will not step the carriage from its tabulation control position.

A better understanding of the present invention may be had from the following description taken in conjunction with the accompanying drawing wherein like reference characters are used to designate similar parts throughout the several figures, and wherein:

Fig. 1 is an elevational view, partly in section, of a keyboard perforator and transmitter embodying the present invention;

Fig. 2 is a fragmental perspective view of the arrangement according to the present invention;

Fig. 3 is a schematic electrical diagram of the perforator magnet operating circuit;

Fig. 4 is a detailed sectional view taken on line 4-4 of Fig. 1; and

Fig. 5 is a detailed sectional view taken on line 5-5 of Fig. 1.

Having reference to Fig. 1, there is shown a receiving printer of the type disclosed in U. S. Patent 1,904,164 to which is associated a tabulator mechanism, a keyboard, a perforator, and a transmitter. This comprises a base portion, indicated generally by the numeral 11, upon which is mounted a typing unit, indicated generally as 12. Associated with the base portion 11 is a perforator, indicated generally as 13, and a transmitting portion, indicated generally as 14. .

Positioned at the rear of the base portion 11 is a pivot rod 15 (Fig. 1), which extends transversely of the base portion. To the pivot rod 15 a plurality of key levers 16 are rotatably mounted which are normally urged upwardly by individual springs (not shown) and which are provided, as is the usual practice, on their forward end with keys (not shown) arranged in banks. Beneath the key levers 16, and extending transversely thereof, are a plurality of pairs of permutation bars 19 and 21. As is well known, the number of pairs of permutation bars corresponds to the number of elements in the permutation code; for example, five or six. The permutation bars 19 and 21 are provided at each end with vertical slots or notches 22 and 23, respectively, which fit over guide combs 24 and 25. The bars 19 and 21 are thus held against longitudinal movement, but are free to be shifted vertically in response to the operation of key levers 16.

Pivotedly mounted on rods 26 and 27 are a pair of rocker arms 28 and 29 interposed between each pair of bars 19 and 21. The rocker arms 28 and 29 are substantially T-shaped, with their free ends formed with off-set lugs on opposite sides of the pivot rods 26 and 27 and spaced some distance therefrom, one of the lugs of each rocker arm projecting forwardly beneath the lower edge of corresponding permutation bars 21, and its other lug projecting rearwardly beneath the companion permutation bars 19. With

this arrangement, the depression of either permutation bar of the pair of bars 19 and 21 rocks the arms 28 and 29 and lifts the companion permutation bar. To the depending portion of each T-shaped rocker arm 28 or 29 is pivotally articulated a longitudinally movable link 31. Thus, when the permutation bars 19 and 21 are moved vertically in accordance with the depression of a key lever 16, the link 31 individual to a pair of the permutation bars 19 and 21 is moved longitudinally, or in a direction of its length.

Each of the key levers 16 is arranged, when operated, to engage and depress one of the permutation bars of each pair of permutation bars 19 and 21 and to set these permutation bars in accordance with a character code combination. The upper edges of permutation bars 19 and 21 are notched to provide high and low portions in accordance with the respective code signals. Also, the bars of each pair of permutation bars 19 and 21 are complementary; that is, the notches of one bar are opposite the projections of its companion bar. The interconnection between the bars of each pair of bars 19 and 21 by means of the rocker arms 28 and 29 prevents the simultaneous depression of two key levers. If an attempt is made to operate more than one key lever, the key levers can only be depressed for a short distance, when they will be blocked by the high portion of the permutation bars 19 and 21. By this construction, the simultaneous depression of two key levers and the transmission of an incorrect signal is prevented.

The perforator 13 comprises a set of code punches 32 movable through an opening in upper and lower guide plates 33 and 34, and cooperative with a guide plate 35 to perforate a tape 36. The plates 33 and 35 are spaced apart to form a tape guide. Intermediate the guide plates 33 and 34 is a stripper plate 37 which cooperates with shoulders on the code punches 32 and a feed hole punch (not shown), and due to the action of springs 38 operates to remove the punches clear of the tape following the operation of a punch hammer 39. The code punches 32 are selectively operated by the actuating member or punch hammer 39 and a set of interponent bars 41 corresponding in number to the punches 32. Operatively associated with each of the bars 41 is a pivoted arm 42 which is connected to a link 31 by means of a connecting bar 43.

The hammer 39 rocks about its pivot 44 and forms the armature of an electromagnet 45. The interponents 41 are adapted to slide on the hammer 39. When the perforating magnet 45 is unenergized, the hammer 39 is retained in its counterclockwise position by a spring 46. Punch hammer 39 carries at the left end thereof a pawl member 47 which cooperates with ratchet teeth 48 of a spacing roller 49 which is also provided with feed pins 51 adapted to mesh with the feed holes which are invariably perforated in the tape 36. Thus, when the magnet 45 is energized and the hammer 39 is rocked to its clockwise position, pawl 47 is raised to engage a tooth 48 on the spacing roller 49. Then, upon the deenergization of magnet 45, spring 46 actuates the hammer 39 to its counterclockwise position and draws the pawl 47 downwardly, which movement causes the spacing roller 49 to be rotated counterclockwise one angular step to effect the spacing of the tape 36 one unit distance.

To prevent repeated operation of the perforating magnet 45 due to the chattering of the operating contact 52 in response to a tremulous touch

of a key and thus to insure a single operation of the perforating magnet 45 upon each depression of a key lever 16, an anti-chatter means is provided. In addition to the five or six pairs of permutation bars 19 and 21, there is provided an additional bar 40, the link 31 of which is connected by a bar similar to 43 to a contact operating lever 50. Associated with contact operating lever 50 is a pair of contacts 52. In the unoperated position of the apparatus, the contact operating lever is held in its clockwise position by a spring 53, which constitutes also a return spring for the universal bar 40, and through control of an insulated striker the contacts 52 are held open. Then, upon the operation of a key lever 16, the contact operating lever 50 is operated counter-clockwise to close the contacts 52, and, at its end 54, it becomes engaged by a latch member 55, thus latching the contacts 52 closed. When the magnet 45 becomes energized and its armature is attracted to rotate the print hammer 39 clockwise, an adjustable striker 57 carried on a bracket 58 integral with print hammer 39 acts upon arm 59 of latch lever 55 to rock the latch 55 counter-clockwise, thus disengaging said latch from the end portion 54 of lever 50 whereupon lever 50 is rocked clockwise by its spring 53 to permit contact 52 to open. It is thus seen that with this anti-chatter arrangement, the energizing of the clutch magnet 45 is independent of a tremulous touch on a key lever 16 since, as soon as the key has been depressed to close contact 52, the latch 55 acts immediately to maintain said contact 52 in the closed position, whereafter they will be opened only upon energization of magnet 45 and operation of hammer 39 through the cooperation of striker 57 and arm 59.

When the perforating mechanism 13 is employed in combination with the keyboard transmitter 14, the permutation links 31 are each provided with a pair of upstanding guide lugs 61. Interposed between each pair of lugs 61 is a depending arm of a locking latch 62, pivoted on a common rod 63. In this manner, locking latches 62 are pivotally articulated to the permutation links 31 and are adapted to be rocked about pivot rod 63 to either of two positions. Associated with latches 62 are a corresponding series of contact levers 64 for making and breaking individual contacts 65. Contact lever 64 cooperates with individual contact cam 66 mounted on the transmitting shaft 67 provided with a clutch mechanism 68 (Fig. 2) controlled by a trip member 56 connected to a universal bar member 69, as set forth in U. S. Patent 1,965,572.

The cams 66 are assembled as a unit and have secured thereto the collar 68, a portion of which is serrated, and is normally urged along the shaft 67 to the right, as viewed in Fig. 2, by a spring 71. Secured to the shaft 67, and arranged to cooperate with the collar 68, is a similarly machined collar 72. The shaft 67 is connected to a source of driving power in a manner such that it is driven continuously, but due to the arrangement of the collars 68 and 72, which constitute a clutch between the shaft 67 and the cams 66, the latter may be selectively rotated.

The spring 71 tends to move the collar 68 along the shaft 67 and into engagement with the collar 72, but this action of the spring is normally prevented by means of a pivoted arm or trip member 56, which has a portion thereof urged into the path of a shoulder 73 formed on the collar 68. The shoulder 73 is also formed with a gradual camming surface, so that as the collar 68 ro-

tates it will cooperate with the associated portion of the stop arm 56 and cause the collar 68 to be moved along the shaft 67 against the action of spring 71 to disengage the serrated portion of the collars 68 and 72 and stop the rotation of the collar 68 and its associate cams 66. Trip member 56 has a horizontal portion 74 which is operatively associated with one arm of a T-shaped lever 75, the depending arm of which is pointed as at 76, and which is normally in the path of a shoulder 77 formed in a trip-off pawl member 78. The member 78 is secured to the universal bail 69 which is rotatably mounted on studs 79, and which is rotated upon the depression of any of the keys of the keyboard.

The universal bail 69 and the member 78 are normally biased to a position shown in Fig. 2 by a spring 81, one end of which is fastened to the member 78, and its other end is secured to a stationary bracket (not shown). When the universal bail 69 is depressed, the member 78, against the action of spring 81, will be moved to the left, as viewed in Fig. 2, and the shoulder 77 will engage the pointed end 76 of the T-shaped lever 75 and cause the stop arm or trip member 56 to be moved, through the depression of portion 74, out of engagement with the shoulder 73 of collar 68. Under these conditions the spring 71 urges the collar 68 to the right, as viewed in Fig. 2, and the serrated portions of the collars 68 and 72 are brought into engagement with each other and the power from shaft 67 is communicated thereto to rotate the cam 66 through one complete cycle. When the cams 66 approach the end of their cycles of rotation, the cam surface preceding the shoulder 73 is effective with the trip member 56 to move the collar 68 against the action of spring 71 and effects the disengagement of the serrated portions of the collars 68 and 72.

The universal bail 69 is urged to its normal position by spring 81 so that the member 78 will likewise be urged to its normal rightward position. Due to the action of a trip-off pawl eccentric 80 in camming the shoulder 77 of trip-off pawl 78 out of engagement with the end 76 of member 75, the latter will be restored to its normal position invariably for each operation of the keyboard mechanism, thus providing a non-repeat mechanism. However, in some instances it is desired to continue the rotation of the cam drum or cam assembly 66 for a longer period, as previously mentioned as one of the objects of the present invention, and for a period sufficient to transmit successively a plurality of groups of impulses of the same character. In order to achieve this result, there is associated with a space bar 82, a member 83, which is fastened to the rod 84 on which the space bar 82 is loosely mounted. Member 83 is provided with a forwardly extending portion 85 having a laterally disposed end 86 adapted to be disposed beneath the space bar 82. Member 83 is also provided with a vertically extending portion 87, to the upper extremity of which is connected a rod 88. The rod 88 has a horizontally extending portion 89 which is normally in alignment with the downwardly extending portion of the T-shaped member 75. Consequently, when the space bar 82 is depressed, it will act through extremity 86 of arm 85 of member 83 to move the rod 88 to the left, as viewed in Fig. 2, and the portion 89 will engage the downwardly extending portion of the T-shaped member 75 and cause its rotation and the corresponding rotation of stop

member 56 for releasing the cams 66 for rotation. The T-shaped lever 75 will be held in a position to retract the stop member 56 from co-operation with shoulder 73 and the cams 66 will be rotated through successive cycles as long as the space bar 82 is held depressed.

To achieve a similar result automatically, the space bar mechanism of the apparatus according to the present invention is provided, as shown in Fig. 2, with an arm 91 fixed to the rod 84. The arm 91 is provided at its extremity with a laterally extending portion 92 which, according to the present embodiment, is located below the key lever 93 identified with the "figures" or "shift" combination. Of course, it is understood that any function key lever can be adopted or used to achieve the object of the present invention. The essential requirement in the choice of key lever is that it should be identified with a code combination wherein the spacing and printing mechanisms are not operated.

Positioned above the key lever 93 is a solenoid 94, the movable core 95 of which is adapted to operate the key lever 93 in a manner to be hereinafter described.

In the operation of the transmitting unit, the depression of a key lever 16 moves the permutation bars 19 and 21 permutably in accordance with a predetermined code combination, the setting of which, through links 31 determines the positions of the locking latches 62. The rotation of the cams 66 is initiated substantially simultaneously with the setting of the locking latches, through the instrumentality of trip member 56, which is acted upon by the universal bar 69. A locking loop 60 (Fig. 1), controlled by a cam 99, carried on the shaft 67, is permitted to rotate in a counterclockwise direction, as viewed in Fig. 1, to lock the latches 62 in their selected position. The setting of latches 62 determines whether the contact levers 64 shall or shall not be operated by their associated cams 66 to transmit, through contacts 65, over a signal line 70, to the receiving station, a predetermined code combination of signaling impulses. The respective notches in the cams 66 are arranged in a helical progression so that upon the rotation of the cam assembly, the contacts 65 controlled by levers 64 will be operated successively. The apparatus herein disclosed is operated in accordance with an equal length letter code in which each code combination is a permutation of marking and spacing conditions, and is preceded by a start impulse and followed by a stop impulse according to the well-known start-stop system.

When the perforator and transmitter are to be operated simultaneously under the control of a key lever 16, means is provided for starting the operation of the perforating device under control of the transmitting devices to insure that the same signal that is transmitted is also invariably perforated in the tape. To achieve this result, two pairs of contacts 101 (Fig. 1) are positioned over two adjacent transmitting cams 66, as more fully disclosed and described in copending application Serial No. 167,139 filed October 4, 1937, by R. A. Lake. The pairs of contacts 101 are mounted on a bracket 102, and associated with each pair of contacts 101 for controlling the operation of the same is a cam follower 103 or 104. In this manner, cam followers 103 and 104 ride into the depression of their associated cams 66, which are the same depressions which act to operate the contact levers 64. The purpose of having two

75 pairs of contacts 101, which are connected in parallel (as shown in Fig. 3) is to impress a longer operating impulse on the perforating magnet 45 than would be obtained under the same condition by a single pair of contacts. The contacts 101 are normally open, and when the transmitting cam distributor (comprising cams 66 and contacts 65) is operated, the circuit for the perforator magnet 45 will invariably be closed for the period of substantially two impulse intervals because of an overlap in the sequential operation of the pairs of contacts 101.

15 The keyboard mechanism shown in Fig. 1 is similar to that described and shown in U. S. Patent No. 1,965,572. With the mechanism shown in said patent, it is desired in some instances to transmit directly to a line circuit code combinations of impulses representative of the character key operated, while in other instances it may be more practical first to perforate a tape in accordance with the key operated, and then to transmit subsequently the signals corresponding thereto by subjecting the tape to a tape transmitter. To provide for the several possible conditions of operation of the mechanism, a switch 20 is arranged in the keyboard apparatus to control the transmission of impulses directly to the line circuit, the perforation of a tape only, or the operation of the transmitting distributor and the perforator simultaneously.

25 To control these various operations, a switch lever 105 (Fig. 1) is provided which is mounted adjacent the transmitting distributor 14. Lever 105 assumes three positions; namely, an upper position 106A (Fig. 3), a middle position 106, and a lower position 106B, and is held in any one of these positions through the cooperation of a bracket 107. As shown in Fig. 3, switch member 105 is provided with a bifurcated end having strikers which cooperate with a group of five contacts 108. The position of the switch member 105 indicated at 106A is known as the "keyboard" position, and is a position wherein only direct keyboard transmission of signals to the line is effected; that is, each time a key lever is operated, the transmitting cam drum is rotated a single cycle to transmit a code combination of signals through contacts 65 to the line. In this position of member 105 all of the five contacts of contact bank 108 are opened.

30 The position of switch member 105, indicated as 106, is known as the "tape and keyboard" position and is that condition of the apparatus wherein the perforator and transmitting mechanisms are operating simultaneously. In this position, the contacts of the contact bank 108 are arranged, as shown in Fig. 3, wherein the lower contact 112 remains closed, and in this position the energizing circuit for the perforating magnet 45 extends from positive battery over conductors 109 and 111, through contact 112, through contacts 101 associated with the transmitting cams, thence over conductor 113, through the winding of the perforating magnet 45, then to negative battery. From the previous description it is observed that contacts 101 are closed periodically, once for each cyclic rotation of the transmitting cam drum. In this manner, the operation of the perforator magnet 45 is assured. The position of the switch member 105 indicated in Fig. 3 as 106B, is known as the "tape" position, and in this position, the automatic tabulating mechanism is not used.

35 According to the present invention, the keyboard perforator and transmitter of the type dis-

closed in U. S. Patent No. 1,965,572 is modified for the production of perforated tape to control the transmission of message matter embodying tabulation operations. To achieve this result, the typing unit 12 is provided with a tabulating mechanism, which will now be described. The typing unit, indicated generally as 12 in Fig. 1, includes a primary selecting mechanism represented by single selector magnet 121, shown in Fig. 1, and is of the T-shaped sword and lever type, disclosed in U. S. Patent No. 1,745,633 issued to S. Morton et al., and a secondary selector or selector vane assembly indicated generally as 122. The selector vane assembly 122 controls, through a set of bell cranks 123, a corresponding set of curved code bars 124 carried in a movable type carriage, indicated generally as 125. As set forth in U. S. Patent No. 1,904,164, this type carriage is movable longitudinally with respect to a stationary platen (not shown), but manifestly the invention is not limited to its application to such apparatus.

The tabulating mechanism which is in accordance with U. S. Patent No. 2,076,864, comprises a tabulator bar 126 extending in front of the printing apparatus, as shown in Fig. 1, and which is provided with depending portions 127 and 128, by means of which it is pivotally mounted on a bracket 129 carried in the printer frame. The tabulator bar 126 is adapted to be swingable toward and away from the type carriage 12, and is also provided with a longitudinal slot 131 extending substantially the entire length of the bar, within which extend movable stop members 132, which are clamped to the bar 126 by means of screws 133 and clamping member 134, (Fig. 2). As indicated in Fig. 4, these stop members 132 are provided with an inclined or cam portion 130, conformed to produce a quick camming-out action upon cooperating with a cam element 120, carried by the type carriage 12, to terminate the tabulating operation.

Tabulator bar 126 is also provided, intermediate the depending portions 127 and 128, and suitably positioned relative to tabulator function lever 135, with another depending portion 136. Attached to and depending from portion 136 is a bar 137, the lower end of which is provided with an aperture 138 (Fig. 2) having its upper right-hand corner formed so as to provide a re-entrant stepped portion 139. The tabulator bar 126 normally tends to move in a clockwise direction, as viewed in Fig. 2, due to the action of a spring 141.

Cooperating with the stepped portion 139 is one arm 142 of a lever 143 pivoted at 144. The extremity of arm 142 is provided with a laterally disposed portion 145 which cooperates with stepped portion 139 of member 137. At the end of arm 146 of lever 143 is carried a vertically extending member 147, the upper end of which is provided with an open ended slot adapted to engage a pin 148 carried by the upper escape-
ment pawl 149 of the spacing mechanism which is fully described and shown in U. S. Patent No. 2,076,864.

The selector vanes 122 control a series of function levers, including the tabulator function lever 135. Function lever 135 is provided on an arm 151 with code notches and projections which cooperate with the vanes of the selector vane assembly 122, and which are coded to correspond with the tabulator signal. Thus, when the vanes 122 are set according to the tabulator signal in

response to the operation of the selector mechanism 121, the tabulator function lever 135 will be selected and will be urged toward the selector vanes 122 by spring 152 about its pivot rod 153.

Function lever 135 is provided with a horizontal portion 154, so conformed that its extremity 155 engages the lower edge of arm 146 of lever 143 so that, when function lever 135 (upon its selection) is permitted to rotate in a counter-clockwise direction under the action of its spring 152, the end 155 thereof is raised, thus rotating lever 143 against the tension of its spring 150. The laterally disposed end 145 of lever 142 is thereby moved downwardly clear of the stepped portion 139, permitting spring 141 to urge the tabulator bar 126 inwardly (or clockwise as viewed in Fig. 2) until wall 156 of member 137 engages the laterally disposed portion 145. Adjustable stops 132 are moved inwardly into the path of a cam member 120 (Fig. 4), which is pivoted at 158 on a portion 159 integrally formed on a bar 161, which is comparable to bar 53, shown in Fig. 1 of Patent 1,904,164, and which is employed for retaining the bell crank levers 123 in operable relation to vanes 122. Cam 120, like bar 161 and bell cranks 123, is movable with the type carriage 125 for carriage spacing, and normally tends to rotate in a clockwise direction about pivot 158 due to the action of a spring 162, but its clockwise rotation is limited by the action of a stop pin 163, carried thereon, with the end of bar 161. Consequently, upon the rightward movement of type carriage 125, as viewed in Fig. 1, cam 120, due to its limited rotatability in a clockwise direction, will, by its camming action on stop members 132, rock tabulator bar 126 outwardly; but upon a leftward movement of type carriage 125, cam 120 upon striking the series of stop members 132, will be rotated counterclockwise against the action of spring 162, avoiding operation of the cam portion 130. When the tabulator bar is thus actuated outwardly by the cam 120, against the action of spring 141, the laterally disposed portion 145 of lever 143 will escape the stepped portion 139 and through the action of spring 150 will resume its upward position shown in Fig. 2.

As a result of the aforementioned operation of lever 143 upon the selection of the tabulator function lever 135, the spacing pawl 149 is lifted out of engagement with the spacing ratchet 165 by the link 147, and is held out of engagement therewith so long as the laterally disposed portion 145 is restrained by the stepped portion 139, which is as long as, or for the period of time which, it takes the carriage 125 to carry the cam 120 to the next tabulator stop 132, when, due to the camming out of the tabulator bar 126, the lever 143 is released to respond to the action of its spring 150, whereupon the spacing pawl 149 is permitted to return into engagement with the ratchet 165 to stop the carriage 125.

It is an object of the present invention to perforate the tape to correspond to the tabulating time as well as for the tabulation initiating code signal. To achieve this result, the tabulator bar 126 is provided with a depending tongue or portion 171 (Fig. 1), the lower end of which cooperates with a bell crank 172 pivoted at 173, Fig. 5, to the base 174. Arm 175 of bell crank 172 cooperates with an insulated button 176 of a contact pair 177 mounted on a bracket 178 fixed to member 129. The pair of contacts 177 is con-

nected in an obvious circuit including the solenoid 94.

General operation

During the normal operation of the apparatus shown in Fig. 1; that is, during the transmission of straight message matter (such as does not involve tabulation), the tabulating bar 126 remains in its counterclockwise position (as viewed in Fig. 2) against the tension of its spring 141, whereat laterally disposed end 145 of lever 142 is in engagement with the vertical or forward edge of step 139 of member 137. In this condition of operation, contacts 177 remain open and consequently the energizing circuit for solenoid 94 is broken. However, in the preparation of messages containing tabular matter, during which the take 36 is simultaneously perforated, it is necessary in the preparation of perforated tape to be used subsequently for automatic transmission, to compensate for the time consumed during the various tabulation operations, which is done in the following manner.

Upon depression of the tabulation key, the pairs of selector bars 19 and 21 are set in a characteristic permutable manner, moving thereby the links 31 to the right- or left-hand longitudinal position. Corresponding permutable settings are given to interference members 41 and locking latches 62. Simultaneously with the depression of the tabulation key, the universal bail 69 is operated, which acts through levers 78 and 75 to release the shaft 67 for rotation through one cycle by permitting the engagement of collars 68 and 72. This causes cams 66 to control the closure of transmitting contacts 65, whereupon signal impulses are impressed on signal selector magnet 121 and interconnected repeater magnets 180, whereupon the selection of the tabulation code is set up on the vanes 122 in the manner described in U. S. Patent No. 2,076,864.

Upon the operation of the main operating shaft, the function lever 135 is permitted to be advanced towards the vanes 122 by its spring 152, and since the code notches on the function lever 135 correspond to the setting of the vanes 122, a selection of the function lever 135 is effected whereupon end 155 of arm 154 of function lever 135 is raised to impart counterclockwise rotation to the tabulating operating lever 143. Through the laterally disposed portion 145, lever 143 is latched in its counterclockwise position, as previously described, to hold the spacing pawl 149 out of engagement with spacing ratchet 165, to initiate continuous spacing of carriage 125 during tabulation. However, when the tabulating bar 126 is actuated inwardly (or clockwise as viewed in Fig. 2) by the spring 141, the depending portion 171 moves outwardly, and in so doing causes bell crank lever 172 to be actuated in a clockwise direction (Fig. 5) to close the contacts 177, to establish the energizing circuit for the solenoid 94. When the solenoid 94 is thus energized, its movable core 95 will be actuated downwardly to cause the depression of the key lever 93, which according to the present embodiment is identified with the "figures" code combination. Key lever 93 upon being so depressed will operate the pairs of selector bars 19 and 21 in accordance with the "figures" code combination, setting the links 31 correspondingly. The setting of links 31 in this manner will effect a corresponding setting of the interference members 41 and the locking latches 62, so that the code combinations perforated in the tape and

the signals transmitted over the wire 70 will correspond to the "figures" code combination. As previously described, key lever 93 also actuates the lever arm 91 through its lateral portion 92 5 to rotate the rod 84, thus imparting corresponding rotation to lever 83. This movement of lever 83 will, through rod 88, rotate lever 75 so as to disengage the trip member 56 from the clutch collar 68. Member 83 and its rod 88 will hold the lever 75 in this position so long as solenoid 94 remains energized. Therefore, the operation of the perforating mechanism 13 and the transmitting mechanism 14 will continue so long as the cam drum 66 is permitted to rotate, and this is timed by the approach of the cam 120 to the tabulator stop 132.

When the cam 120 reaches the tabulator stop 132, the tabulator bar 126 will be cammed outwardly and the laterally disposed portion 145 of lever 143 will ride off the step portion 139 and be returned to its clockwise position by its spring 150, thereby permitting the upper space pawl 149 to return into engagement with spacing ratchet 165 to stop the progress of the carriage. At the same time, the depending portion 171 is returned to its inward or counterclockwise position, thus permitting bell crank 172 to be returned to its counterclockwise position (as viewed in Fig. 5) by its spring 170, thus permitting the contacts 30 177 to open, thereby breaking the energizing circuit for the solenoid 94. When this occurs the solenoid core 95 will be retracted or actuated upwardly to permit the key lever 93 to be restored to its upward or unoperated position. This will permit rod 84 to be rotated clockwise to impart similar rotation to lever 83, whereby rod 88 will be actuated rightwardly (as shown in Fig. 2) to become disengaged from lever 75, thus permitting the clutch trip lever 56 to engage the collar 68 of the clutch to stop the shaft 67 from rotation. 40 In this condition the mechanism is not only in readiness for the next tabulation operation but also for any subsequent key operation.

With the apparatus just described, a printed 45 copy or home record is produced, corresponding to the perforations made in the tape. Furthermore, not only is a home record made of ordinary straight matter, but a record is made of matter containing tabulated portions, and the 50 perforated tape is so produced as to compensate for the tabulating time, so that when utilizing the tape for retransmission, transmission need not be suspended during tabulation time because sufficient non-spacing and non-printing code 55 combinations of tabulating continuing nature have been perforated in the tape to permit the carriage at the remote printers to move between tabulation stops. With the apparatus according to the present invention, the perforated tape is 60 made to correspond with variable tabulating periods so that there is no undue loss of line time.

Although a particular embodiment of the invention has been described herein, it will be understood that the apparatus is capable of many 65 modifications, and it is contemplated that all changes which come within the range and scope of equivalency are intended to be embraced within the purview of the appended claims.

What is claimed is:

1. In a telegraph system, a transmitter, selector mechanism for controlling the effectiveness of said transmitter, a receiver responsive to signaling conditions comprising a circuit controlling means, and electromagnetic means controlled by said circuit controlling means for controlling the

effectiveness of said selector mechanism during certain periods of operation of the receiver.

2. In a telegraph system, a transmitter, selector mechanism for exercising a predetermined control over said transmitter, a receiver responsive to signaling conditions comprising an electromagnetic device, and means controlled by said device for varying the control exercised by said selector mechanism.

3. In a telegraph system, a perforator, means for exercising a predetermined control over said perforator, a receiver responsive to signaling conditions comprising a solenoid, signal responsive means in said receiver for controlling said solenoid, and means controlled by said solenoid for varying the control exercised by said first recited means.

4. In a telegraph apparatus, a plurality of signal determining means, selector mechanism for exercising a predetermined control over said means, a movable carriage, tabulating mechanism effective under control of said selector mechanism to control the uninterrupted advancement of said carriage through a plurality of spaces at a time, and an electromagnetic device controlled by said tabulating mechanism to vary the control exercised by said selector mechanism during said uninterrupted advancement of said carriage.

5. In a telegraph apparatus, a plurality of signal determining means, selector mechanism for exercising a predetermined control over said means, a movable carriage, tabulating mechanism effective under control of said selector mechanism to control the uninterrupted advancement of said carriage through a plurality of spaces at a time, a solenoid, a circuit therefor, and circuit controlling means controlled by said tabulating mechanism to vary the control exercised by said selector mechanism during said uninterrupted advancement of said carriage.

6. In a telegraph system, the combination of a manually operable keyboard mechanism, a tabulator mechanism responsive thereto, a tape perforator responsive to control by said keyboard mechanism, means in said keyboard mechanism to initiate operation of said perforator, a solenoid and a circuit therefor, and circuit controlling means in said tabulator mechanism effective through said solenoid to continue operation of said perforator during the operation of said tabulating mechanism.

7. In a telegraph system, a signal determining means, selector mechanism for controlling the effectiveness of said signal determining means, means responsive to signaling conditions comprising a circuit controlling means, and electromagnetic means controlled by said second recited means for controlling the effectiveness of said selector mechanism during certain periods of operation of the receiver.

8. In a telegraph system, a signal determining means, a selector mechanism for controlling the effectiveness of said signal determining means, a tabulating mechanism responsive to signaling conditions comprising a circuit controlling means, and electromagnetic means controlled by said circuit controlling means for controlling the effectiveness of said signal determining means during certain periods of operation of said tabulating mechanism.

9. In a telegraph system, a signal determining means, selector mechanism for controlling the effectiveness of said signal determining means, tabulating mechanism responsive to signaling

conditions comprising a circuit controlling means, a repeat mechanism, and electromagnetic means controlled by said circuit controlling means for controlling through said repeat mechanism the effectiveness of said selector mechanism during the periods of operation of said tabulating mechanisms.

10. In a telegraph system, signal determining means, means for controlling the effectiveness of said signal determining means, a receiver responsive to signaling conditions including a tabulating instrumentality, a circuit controlling means controlled by said instrumentality, means for producing a tabulation-time-continuation signal, and electromagnetic means controlled by said circuit controlling means for holding said last mentioned means operative during the period of operation of said tabulating mechanism.

11. In a telegraph apparatus, a platen, type carrying mechanism, means for producing relative movement between said platen and said type carrying mechanism, a plurality of signal determining means, selector mechanism for exercising a predetermined control over said means, tabulating mechanism effective under the control of said selector mechanism to control uninterrupted-ly the relative movement between said platen and said carriage a predetermined amount, and an electromagnetic device controlled by said tabulating mechanism to vary the control exercised by said selector mechanism during said uninterrupted movement.

12. In a telegraph system, a perforator, means for exercising a predetermined control over said perforator, a receiver responsive to signaling conditions comprising a circuit controlling means, and means controlled by said circuit controlling means for varying the control exercised by said first recited means.

13. In a telegraph system, a perforator, means for exercising a predetermined control over said perforator, a receiver responsive to signaling conditions comprising a circuit controlling means, and electromagnetic means controlled by said circuit controlling means for varying the control exercised by said first recited means.

14. In a telegraph system, a transmitter, a selector mechanism for controlling the effectiveness of said transmitter, a receiver responsive to signaling conditions including a circuit controlling means, and electromagnetic means at said receiver controlled by said circuit controlling means for controlling the effectiveness of said selector mechanism during certain periods of operation of the receiver.

15. In a telegraph system, a transmitter, a key operated selector mechanism for controlling the effectiveness of said transmitter, a receiver responsive to signaling conditions including a circuit controlling means, an electromagnetic means at said receiver controlled by said circuit controlling means for controlling the effectiveness of said key operated selector mechanism during certain periods of operation of the receiver.

16. In a telegraph system, a transmitter, selector mechanism for determining the signals to be transmitted, a receiver responsive to transmitted signals, a movable carriage in said receiver, tabulating mechanism under the control of the transmitter to advance the carriage a predetermined number of spaces, and electromagnetic means operated by said tabulating mechanism to cause the transmitter to transmit nonspacing signals during the advancement of the carriage by the tabulating mechanism.

17. In a telegraph system, a transmitter, a selector mechanism for determining the signals to be transmitted, a receiver responsive to transmitted signals, a tabulating mechanism associated with said receiver and under the control of the transmitter including circuit controlling means, and electromagnetic means controlled by said circuit controlling means to cause the transmitter to transmit nonspacing signals during the operation of the tabulating mechanism.

18. In a telegraph system, the combination of a transmitter, printing mechanism and perforating mechanism responsive to said transmitter, selector mechanism for controlling said transmitter, and a tabulating mechanism under the control of said transmitter including electromagnetic means to control said printing and perforating mechanisms.

19. In a telegraph system, the combination of a transmitter, printing mechanism and perforat- 20

ing mechanism responsive to said transmitter, selector mechanism for controlling said transmitter, a tabulating mechanism under the control of said transmitter including circuit controlling means, and electromagnetic means controlled by said circuit controlling means to control said printing and perforating mechanisms.

20. In a telegraph system, a combination of a transmitter, printing mechanism responsive to said transmitter, perforating mechanism also responsive to said transmitter for perforating signal combinations on a tape, selector mechanism for controlling said transmitter, and tabulating mechanism under the control of the transmitter including electromagnetic means to cause said perforator to perforate nonspacing code combinations in said tape during the operation of the tabulating mechanism.

RAYMOND E. ZENNER.
